UNITED STATES PATENT OFFICE.

JOHN H. RAMBERG AND OTTO A. MERMAN, OF MINNEAPOLIS, MINNESOTA.

WINDOW-FRAME AND SLIP-SILL FOR DROP-SASHES.

1,272,093.

Specification of Letters Patent.

Patented July 9, 1918.

Application filed July 11, 1917. Serial No. 178,898.

To all whom it may concern:

Be it known that we, JOHN H. RAMBERG and OTTO A. MERMAN, citizens of the United States, residing at Minneapolis, in the 5 county of Hennepin and State of Minnesota, have invented a new and useful Window-Frame and Slip-Sill for Drop-Sashes; and we do hereby declare the following to be a full, clear, and exact description of the 10 invention, such as will enable others skilled in the art to which it appertains to make and use the same.

This invention relates to an improved slip sill and window frame for lowerable or 15 drop sashes, and one of the objects of the invention is to provide a window frame of this kind having a pocket or box in its lower portion for the reception of the upper and lower sashes, and in combination with 20 a slip sill for covering the opening to the pocket or box, thereby entirely concealing the sashes.

A further object of the invention is to provide an improved slip sill window and 25 frame therefor, whose construction will provide, as near as possible, a substantially weather-, water- and dust-proof sill, when the sashes are raised or dropped or lowered entirely into the pocket or box of the window frame.

A further object of the invention is the provision of an improved water tight slip window sill, when the sashes are raised or lowered.

35 A further object of the invention is to provide a device of this kind in which the upper and lower sashes may be dropped or lowered into a pocket or box below the sill, without in any way moving the storm sash or screens.

40 A further object of the invention is the provision of an improved slip sill for windows, whose operation will permit the screens or storm sash to be placed adjacent the outside of the window frame and not be moved when the sill is operated.

45 A further object of the invention is the provision of an improved window frame provided with a sectional window sill, the sections of which being so hinged and capable of hinged movements, whereby the sections may be tilted so that the upper 50

and lower sashes may be moved or lowered or dropped into a pocket below the sill.

A further object of the invention is the 55 provision of means formed in the inner and outer guide rails of the window frame to permit the sections of the sill to be swung open, whereby the upper and lower sashes may be lowered or dropped. 60

In practical fields, the details of construction may necessitate alterations falling within the scope of what is claimed.

The invention comprises further features and combination of parts, as hereinafter set 65 forth, shown in the drawings and claimed.

In the drawings:—

Figure 1 is a view in elevation of a portion of the side wall or the side of a house, showing the improved window frame with a 70 pocket for the upper and lower sashes, as applied.

Fig. 2 is a vertical sectional view on line 2—2 of Fig. 1, showing the sashes lowered.

Fig. 3 is a vertical sectional view through 75 the window frame and its pocket, showing the sashes raised.

Fig. 4 is an enlarged sectional view of the window frame, showing the sectional window sill as applied, illustrating the sections 80 of the sill open in dotted lines.

Fig. 5 is a sectional view on line 5—5 of Fig. 4.

Fig. 6 is a sectional view on line 6—6 of 85 Fig. 5.

Fig. 7 is a detail view of one end of one of the sill sections, showing a weather strip for the end of the section.

Referring more especially to the drawings, 1 designates a window frame, which 90 may be of any conventional construction, with the exception that the same shall be of sufficient length, whereby its lower portion substantially for one-third of its length, may be extended downwardly between the 95 inner wall 2 of the house or dwelling and the outer wall 3 thereof, thereby forming a pocket 4, for the reception of either one or both of the upper and lower sashes 5 and 6. The sides of the window frame are provided with the inner and outer stop guide rails or strips 7 and 8, and the parting strip 9, which is disposed substantially intermediate the inner and outer strips 7 and 8, and

by means of the parting strip 9, the upper and lower sashes are guided in order that they shall not interfere with each other in their movements. It is to be noted that the 5 stop guide strip 8 on each side of the window frame is inserted between the portion 10 of the frame and the outer strip or portion 11 of the frame, and held so inserted by means of the tongue and grooved con- 10 nections 12 and 13, as more clearly shown in Fig. 5. The rib 14 of this strip 8 really acts as the guiding means for the upper sash, that is, together with the parting strip, which is inserted, as at 15 into the portion 15 10 of the window frame. The lower part of each strip 8 is provided with a recess 16. These recesses are oppositely disposed, and the sill of the window frame comprises the inner and outer stationary sill sections 17 20 and 18, and the intermediate hinged or movable sections 19 and 20. The outer edge portion of the stationary section 17 is provided with a rabbet 21, and to the vertical wall of this rabbet one leaf of each hinge 22 is secured by the screws 23. The other leaf of each hinge 22 is secured to the inner edge of the movable sill section 19 by the screw 24, whereby, when the section 19 is lowered, as shown in Fig. 4, its inner por- 25 30 tion will rest in the rabbet 21. The stop guide strip 7, at its lower portion is provided with a recess 25. The recesses 25 of both strips 7, only one of which is shown, are designed to be directly opposite to each 35 other. The lower wall 26 of each recess 25 is curved on an arc concentric with the hinge 22, whereby the extension 27 of each end of the sill section 19 may swing or move into the recess 25, when the sill section 19 40 is raised, as shown in dotted lines in Fig. 4, to permit the lower sash to be dropped or lowered into the pocket 4. The stationary sill section 18 is provided with a rib or flange 28, over which the curved flange 29 45 of the sill section 20 extends, whereby the edge of the flange 29 may engage or rest on the upper face of the sill section 18. Owing to such over-extending of said flange 29 and the overlapping of the sill sections 50 55 19 and 20, water easily sheds off the window sill. Secured to the sill section 18 by means of suitable screws 30, is one of the leaves of the hinge 31, while the other leaf is secured to the outer curved surface of the flange 29 60 of the sill section 20. The hinge extends up from the sill section 18, thereby supporting the sill section 20, spaced from the section 18, so that water can shed, and to permit cleaning under the section 20. The sill section 20, when opened may be positioned so that its end may enter the recess 16. The inner portion of each end of the sill section 20, in fact its corner, is cut away, as shown at 32 to make room for the parting strip 9, 65 when the sill section 20 is lowered, as shown

in full lines in Fig. 4. Where the inner portion of the sill section 20 is adjacent the parting strip 9, when said section 20 is lowered, the parting strip has a notch 33, the lower end of which supports the sill section 20. It is to be observed that the sill sections 19 and 20, when lowered, as shown in full lines, overlap each other. The under-face of the outer portion of the section 19 is provided with a longitudinal groove or 70 recess 34, for the reception of the correspondingly shaped sheet metal plate 35. This sheet metal plate 35 is bent to provide the portion 36 which is engaged by the upper inner edge of the sill section 20, and 75 to provide the groove 37, for the reception of the plate 38, which is secured as at 39 to the sill section 20. This sheet metal plate 34 is provided to insure a tight connection between the two sill sections 19 and 20. 80 Said plates 34 and 38 may be constructed of any suitable material other than metal; if need be, they may be constructed of a suitable material that will not only exclude dust, but also water. However, if constructed of 85 metal, which is preferable, the connection between the two plates may be such as to exclude dust and the like. The side walls of the window frame between the stop guide strips 7 and 8 and the parting strip are each 90 provided with suitable grooves 40 for the reception of the weight bands or cords 41 of the weights 42 and said upper and lower sashes. The lower part of each side of the window frame just above the stationary sill 95 section 18 and between the parting strip 9 and the stop guide rail 8, is provided with an angular recess 43, into which a sheet metal spring angular weather strip 44 (one of which is secured to each end of the sill 100 section 20) engages or springs, which not only acts as a weather strip and to close one of the grooves 40 to exclude dust and water, but also to substantially latch the sill section 20 in its lowered position, as shown in 105 full lines in Fig. 4. By opening the sill sections 19 and 20, as shown in dotted lines in Fig. 4, said upper and lower sashes may be lowered or dropped within the pocket 4, after which said sill sections may be closed. 110 The window frame and the various stationary and movable sill sections may be constructed in any suitable proportion, and made from any suitable material, and the groove 28, and such other minor details may 115 be varied or altered in their detail construction and proportion within the scope of the claims appended hereto. By means of this improved sectional sill, one or more of the sections being movable, and by virtue of 120 said movable and pocketed upper and lower sashes, said sashes may be adjusted in any desired positions or pocketed in the manner described, without removing the storm sash or window screen 45 (which is arranged 125 130

within the window and resting on the stationary sill section 18), or the screen or storm sash may be removed or detached, without removing the upper or lower window sashes, and vice versa.

The invention having been set forth, what is claimed as new and useful is:—

1. In combination, a window frame provided with a sill, and a pocket below the 10 sill, said sill comprising inner and outer stationary sill sections and intermediate movable overlapping sill sections, each being hinged to the inner edge portion of an adjacent stationary sill section.

15 2. In combination, a window frame provided with a sill, and a pocket below the sill, said sill comprising inner and outer stationary sill sections and intermediate movable overlapping sill sections, each 20 being hinged to the inner edge portion of an adjacent stationary sill section, said intermediate movable sill sections having their overlapping parts provided with interengaging connections.

25 3. In combination, a window frame having a sill and a pocket below the sill for the reception of the upper and lower sashes of the window, said sill comprising inner and outer stationary sill sections and intermediate 30 pivotally movable sill sections, means for hingedly mounting one of the movable sill sections on the outer stationary sill section, so as to permit the upper surface of the outer stationary sill section to be cleaned, 35 and whereby the water will shed from the outer stationary sill section and adjacent movable sill section, and means for hinging the other movable sill section to the inner stationary sill section.

40 4. In combination, a window frame having a sill and a pocket below the sill for the reception of the upper and lower sashes of the window, said sill comprising inner and outer stationary sill sections and intermediate 45 pivotally movable sill sections, means for hingedly mounting one of the movable sill sections on the outer stationary sill section, as to permit the upper surface of the outer stationary sill section to be cleaned, 50 and whereby the water will shed from the outer stationary sill section and adjacent movable sill section, and means for hinging the other movable sill section to the inner stationary sill section, the inner faces of 55 the sides of the window frame having re-

cesses for the reception of the ends of the movable sill sections, whereby the inner walls of said recesses will act as stops to limit the movable sill sections in their open 60 positions.

5. In combination, a window frame having a sill and a pocket below the sill for the reception of the upper and lower sashes of the window, said sill comprising inner and outer stationary sill sections and intermediate 65 pivotally movable sill sections, means for hingedly mounting one of the movable sill sections on the outer stationary sill section, so as to permit the upper surface of the outer stationary sill section to be cleaned, 70 and whereby the water will shed from the outer stationary sill section and adjacent the movable sill section, and means for hinging the other movable sill section to the inner stationary sill section, the inner faces of 75 the sides of the window frame having recesses for the reception of the ends of the movable sill sections, whereby the inner walls of said recesses will act as stops to limit the movable sill sections in their open 80 positions, the inner faces of the sides of the window frame at their lower portions having angular recesses adjacent the movable sill section hinged to the outer stationary 85 sill section, and spring sheet metal devices 90 on the ends of one of the movable sill sections to engage said angular recesses.

6. In combination, a window frame provided with a sill, and a pocket below the 90 sill, said sill comprising inner and outer stationary sill sections and intermediate movable overlapping sill sections, each being hinged to the inner edge portion of an adjacent stationary sill section, the inner 95 faces of the sides of the window frame at their lower portions having angular recesses adjacent the movable sill section hinged to the outer stationary sill section, and spring sheet metal devices on the ends of one of the movable sill sections to engage said angular 100 recesses.

In testimony whereof we have signed our names to this specification in the presence of two subscribing witnesses.
